UNITED STATES PATENT OFFICE.

MILTON C. PETERS, OF OMAHA, NEBRASKA.

MIXING APPARATUS.

No. 914,304.

Specification of Letters Patent.

Patented March 2, 1909.

Application filed May 20, 1907. Serial No. 374,672.

To all whom it may concern:

Be it known that I, MILTON C. PETERS, a citizen of the United States, residing at Omaha, in the county of Douglas and State of Nebraska, have invented certain new and useful Improvements in Mixing Apparatus; and I do hereby declare the following to be a full, clear, and exact description of the invention, such as will enable others skilled in the art to which it appertains to make and use the same.

My invention relates to an apparatus for mixing mortar and the like, and it consists in the construction and arrangement of parts, as will be hereinafter described and particularly pointed out in the claim.

In the drawings:—Figure 1 is a top plan view of the improved mixing conveyer. Fig. 2 is a transverse, sectional view of the mixing conveyer taken on line 2—2 of Fig. 1. Fig. 3 is a detail, perspective view of one of the collars and angular blade. Fig. 4 is a detail, perspective view of a collar and blade arranged for the shaft opposite to the shaft upon which the collar shown in Fig. 3 is employed.

Like characters of reference designate corresponding parts throughout the several views.

The improved mixing conveyer forming the subject-matter of this application comprises a pair of angular shafts 10 and 11 journaled at adjacent ends as in the boxes 12 and 13 and at their opposite ends extending through the end portion 14 of the casing.

The casing preferably comprises side walls 15 and 16 within which is disposed a lining 17 of any approved form as provided with parallel, concave, trough-like portions 18 and 18' separated by a ridge 19 substantially mid-way between the shafts 10 and 11.

The shafts 10 and 11 are intergeared by means of gears 20 and 21, and power applied thereto in any approved manner as by a gear 45 22 carried upon one of said shafts as upon the shaft 11. The shafts 10 and 11 may be of any approved form in cross section and are here shown as square to receive a plurality of collars 23 and 24 which said collars are 50 provided with openings 25 and 26, respectively, conforming to the shafts 10 and 11 and are secured upon the said shafts contiguous to each other and rigidly by any approved means as the set screws 27, which are 55 inserted through holes 28 and 29 of the proper dimensions and engage against the

shafts 10 and 11 and securing collars rigidly thereupon.

The collars 23 and 24 are provided with blades 30 and 31, respectively, disposed at 60 reverse inclinations to each other as shown particularly in Figs. 2, 3 and 4, the said collars being preferably disposed upon the shafts 10 and 11 in such relative positions that as the shafts rotate in the directions indicated by the arrows in Figs. 1 and 2, corresponding blades upon the shafts are disposed opposite each other and the blades on each shaft are spirally arranged. In this manner the shafts need be spaced apart only 70 at such distances that the blades of one shaft will clear the collar portion upon the other shaft, the blades themselves never coming into engagement. As shown in Figs. 1 and 2 the collars at the bottom of Fig. 1 and the 75 first collar seen in Fig. 2 are so disposed that the blade upon shaft 11 extends upwardly while the corresponding blade upon shaft 10 extends downwardly. The second collars are so disposed that the blades of the shafts 80 10 and 11 extend to the right, while in the next position the blade of shaft 10 extends upwardly and the blade of shaft 11 downwardly. It will thus be seen that as the shafts rotate in the direction indicated by 85 the arrow the tendency of the blades is to throw the material over the ridge 19 into position for engagement by the blades of the opposite shaft and that when the blades of the opposite shaft engage the material, the 90 said material is thrown back again. The angularity of the blades is such, however, that when material is delivered to the casing at or adjacent the cross piece 14, the engagement thereof by the blades will move 95 the material toward the opposite end, it being discharged therefrom in any approved manner as through the opening 32 formed in the bottom of the casing or in any other approved manner. It will also be observed 100 that material is discharged from the lower edge of one blade on a given shaft to the upper edge of the next blade on the adjoining shaft, the reverse inclination permitting this, and that the blades are of such size and 105 are so arranged with reference to each other, as shown in the drawings, that a substantially continuous floor is formed, in successive sections, by the blades as the shafts revolve. Material adhering to the blades temporarily will be carried over and into that 110 portion of the casing outside of the shafts and

will then be again conveyed by the blades to the space between the shafts.

What I claim is:—

A mixing apparatus comprising a casing 5 with a plurality of concave bottoms therein which are divided by an upwardly extended longitudinal rib, a rotatable shaft for each of the bottoms having collars thereon provided with blades which are constructed 10 concave-convex their entire lengths, and arranged spirally at an angle to their respective shafts, said shafts being spaced a suitable distance apart and the blades on one

shaft extending to near the collars on the opposite shaft and forming substantially a 15 continuous floor, so as to be adapted to throw the material in continuous masses over the ridge into the adjoining concave bottom, substantially as specified.

In testimony whereof I affix my signature 20 in presence of two witnesses.

MILTON C. PETERS.
